Atty's.

UNITED STATES PATENT OFFICE.

HIRAM L. HENDERSON, OF SYRACUSE, NEW YORK.

APPARATUS FOR DRYING LUMBER.

Application filed February 21, 1927. Serial No. 169,852.

This invention relates to an apparatus for drying lumber and analogous uses in which it is necessary to ventilate the moisture laden air from the drying chamber and to replace the same with fresh air which is preferably heated and moistened in transit to the drying chamber.

This ventilation of the moisture laden air and influx of the fresh air together with the supply of the necessary moisture is preferably regulated by suitable valves or dampers but owing to the widely fluctuating conditions of external atmospheric temperatures, humidities and air velocities together with the varying qualities, quantities, thicknesses and moisture content of different kinds of lumber it is found to be commercially impracticable to maintain the proper drying conditions in the drying chamber by the manual operation of the dampers and valves.

The main object therefore of the present invention is to render these operations substantially automatic and dependent upon the temperature and humidity of the air entering and leaving the kiln.

Another object is to provide means whereby a series of dampers controlling the ventilation and recirculation may be automatically and simultaneously operated from a single source of power preferably by thermally - controlled fluid - pressure - operated means.

A further object is to provide a mixing chamber discharging into the heating chamber and provided with separate inlet ports communicating respectively with the drying chamber and with the atmosphere and controlled by a single damper for regulating the recirculation of the air from the drying chamber to the heating chamber and also for regulating the amount of fresh air to be mixed with the recirculating air in transit to the heating chamber.

Another object is to operate the dampers in conjunction with a steam spraying or other moisture supplying device adapted to discharge into the outlet of the mixing or recirculating chamber in such manner that the dampers will close as the moisture supply increases and open as the moisture supply decreases, and thereby to automatically conserve the steam and at the same time to

maintain more efficient and expeditious drying conditions in the drying chamber. 55

Other objects and uses will be brought out in the following description.

In the drawings:

Figures 1 and 2 are vertical sectional views of portions of a lumber drying kiln 60 taken respectively on lines 1-1, Figure 2 and 2-2, Figure 1.

As illustrated, this kiln comprises a drying chamber —A—, a heating chamber —B— and a mixing chamber —C—, all 65 incorporated within a suitable building structure —1— having a ventilating stack —2— of any suitable height, not necessary to herein illustrate or describe.

The drying chamber —A— and heating chamber —B— are disposed in horizontal planes one above the other and above the outlet of the mixing chamber —C— so that the air heated in the heating chamber may pass by its own lighter specific 70 gravity upwardly through and into contact with the material to be dried within the drying chamber.

This material such as a pile or stack of lumber —L— is mounted upon a carriage 80 —3— having wheels or rollers —4— adapted to travel upon the rails —5— of a track, said rails being supported upon horizontal partitions or floors —6— forming a part 85 of the building structure —1—.

Suitable means is provided for heating the air in the chamber —B— for entrance into the bottom of the drying chamber —A—, said means consisting, in this instance, of a battery of steam pipe coils —7— 90 which may be arranged in tiers one above the other upon supporting members —8—, the latter being supported from the rails —5— by hangers —8—, Figure 2.

Steam may be supplied to the pipe coils —7— from any available source, not shown. The horizontal partition —6— is disposed in a plane substantially midway between the drying chamber —A— and heating chamber —B— which chambers communicate 100 with each other through a relatively large intervening opening.

The substructure of the drying chamber below the horizontal partition or floor —6— is provided with a fresh air inlet opening 105 —9— communicating with the external at-

mosphere for permitting the inflow of fresh air into the mixing chamber —C— through a port —10— just below the floor —6— and above the lower discharge end of the mixing chamber.

The drying chamber —A— is provided with one or more ventilating ports —11— communicating with one or more ventilating stacks or flues —2— which open to the atmosphere and serve to carry off excess moisture laden air from the drying chamber.

Each ventilating port —11— is controlled by a damper —12— which, in this instance, is mounted upon a rock shaft —13—, said rock shaft being journaled in suitable bearings —14— on the frames —15— surrounding the ventilating ports —11—.

This rock shaft extends through the outer wall of the building structure —1— and is provided at its outer end with a crank arm —16— adapted to be operated by a thermally controlled fluid-pressure-operated device —17— through the medium of a connecting arm 18.

The mixing chamber —C— in addition to being connected through the port —10— with the fresh air inlet —9— is also connected by a port —19— to the drying chamber —A— whereby a part of the more or less moisture-laden air in the drying chamber may pass into and through the mixing chamber and thence through an outlet conduit —20— into the heating chamber —B— below the heaters —7—.

A moisture supplying device consists, in this instance, of a steam spray nozzle —21— mounted within the conduit —20— to discharge steam through the open end of said conduit into the lower portion of the heating chamber —B—.

This steam moisture supplying nozzle —21— may be connected to any available source of steam supply through the medium of a pipe —22— having a valve —23— at the exterior of the heating chamber.

This valve —23— is adapted to be opened and closed by a fluid-pressure-operated device —24— of any well-known construction.

The port —19— connecting the drying chamber —A— with the mixing chamber —C— constitutes what may be termed a recirculating port which, together with the fresh air port —10—, is controlled by a damper —25— for regulating the mixture of the fresh air with the recirculating air.

The valve —25— is operatively connected to and actuated by the rock shaft —13— for simultaneous movement with the ventilating damper —12— and is controlled by the same source of power such as the pressure operated device —17—.

The action of the fluid-pressure-operated devices —17— and —24— is primarily and thermally controlled, preferably through the

medium of what is known as a wet bulb —26— to which water may be supplied from any available source through a conduit —27— having a controlling valve —28—.

The wet bulb —26— is connected by a tube —29— to a thermostatically controlled fluid-pressure-regulating device —30— which in turn is connected by branch pipes —31— and —32— to the fluid-pressure-motors —17— and —24— respectively.

The ventilating damper —12— and fresh air damper —25— are both secured to the some rock shaft —13— for simultaneous operation and are arranged in such relation that the opening of either will effect a corresponding opening of the other and vice versa so that when the air in the drying chamber contains an excessive amount of moisture its effect upon the wet bulb —26— will cause the simultaneous operation of both of the fluid-pressure-operated devices —17— and —24— for opening the ventilating valve —12— and fresh air valve —25— to allow the escape of the excess moisture laden air from the drying chamber through the stack port —11— and to admit a corresponding amount of fresh air through the port —10— into the mixing chamber where it mixes with a part of the recirculating air from the drying chamber to take up a part of the moisture content at which time the steam spray-controlling valve —23— will have been opened to allow a jet of steam to be projected with the mixture into the heating chamber below the heating coils —7— after

which the moistened air mixture will be heated and caused to circulate upwardly thru the material to be dried for additionally removing the moisture therefrom.

On the other hand, as the humidity of the air in the drying chamber decreases its effect upon the wet bulb —26— will allow partial collapse or retraction of the fluid-pressure-operated devices —17— and —24— to proportionately close the dampers —12— and —25— across their respective ports —11— and —10— and at the same time to effect a corresponding closing of the steam spray controlling valve —23—.

As the ventilating valve —12— and fresh air valve —25— are closing or closed the recirculating port —19—, which is always open, allows the air within the drying chamber containing a safe or efficient moisture content to recirculate through the mixing chamber —C— and thence through the conduit —20— into the heating chamber below the heating coils.

The wet bulb thermostat or thermostats also automatically control the wet bulb temperature by opening, closing or throttling the steam sprayers or jets —21—.

It will be understood from the foregoing description that any number of ventilating dampers as —12— and any number of fresh

air regulating dampers as —25— may be mounted upon and operated by the same rock shaft as —13— which is automatically controlled through the medium of the wet bulb 5 —26—, thermostatic control —30— and fluid-pressure-operated device —17— and that the valve —23— controlling the extra steam moisture supply through the steam nozzle —21— may be controlled by the same 10 wet bulb as —26— and thermostatic regulator —30—, all of which serve to automatically regulate the temperature and humidity of the air in the drying chamber by opening the fresh air and ventilating dampers as the 15 wet bulb temperature increases and to close said dampers when the wet bulb decreases.

The recirculating air together with the steam admitted to the heating chamber

through the conduit —20— may be deflected upwardly from the open end of said conduit 20 by a deflecting member —33— as shown in Figure 2.

What I claim is:—

In a dry kiln having a drying chamber and a heating chamber communicating with 25 each other through a recirculating passage having a fresh air inlet port, said drying chamber having a ventilating port, separate dampers for said ports, a rock shaft connecting said dampers, fluid-pressure-operated 30 means for rocking the shaft and thermally-controlled means for varying the fluid-pressure in said fluid-operated means.

In witness whereof I have hereunto set my hand this 9th day of February, 1927.

HIRAM L. HENDERSON.
